STANISLAO CILETTI, OF NEWARK, NEW JERSEY.

TOY.

1,168,605.

Specification of Letters Patent. Patented Jan. 18, 1916.

Application filed November 19, 1914. Serial No. 872,964.

To all whom it may concern:

Be it known that I, STANISLAO CILETTI, a citizen of the United States, and a resident of Newark, in the county of Essex and State 5 of New Jersey, have invented certain Improvements in Toys, of which the following is a specification.

This invention relates more particularly to that class of toys which are movable 10 upon wheels and have some part or parts adapted to be automatically actuated as the toy runs along for attracting a child's attention.

The objects of the invention are to provide 15 an improved toy of this character; to provide an improved motor or actuating means; to enable the motor spring to be attached directly to the frame of the toy; to allow the toy to continue running after the 20 motor stops; to actuate the automatic part of the toy from said motor independent of rotation of the wheels; to secure improved means for mounting the automatic part of the toy and transmitting motion thereto; to 25 secure simplicity of construction and operation, and to obtain other advantages and results as may be brought out in the following description.

Referring to the accompanying drawings, 30 in which like numerals of reference indicate the same parts throughout the several views, Figure 1 is a side elevation of a toy embodying my invention; Fig. 2 is a transverse sectional view on line A—A 35 thereof, and Fig. 3 is a transverse sectional view on line B—B of Fig. 2.

In the specific embodiment of the invention illustrated in said drawings, the reference numeral 1 indicates a vehicle having 40 front and rear wheels 2, 3 respectively. The rear wheels 3, 3 are connected to rotate with an axle 4 which extends between the side frames 5, 5 of the vehicle. Above the axle 4 is mounted the motor or propelling 45 means for actuating the toy, said motor including a shaft 6 rotatably supported at its ends in said side frames parallel to the axle. Adjacent one end of said shaft within the frame, is a gear wheel 7 in mesh 50 with a pinion 8 fast upon the axle 4 adapted to drive said axle and wheels when rotated. Preferably said gear wheel 7 is greater in diameter than the pinion 8 so that the vehicle will be caused to travel 55 a considerable distance with only a few revolutions of the gear wheel, but obviously

the proportions of the gear wheel and pinion may be varied without departing from the spirit and scope of the invention, and I do not wish to be understood as restricting myself to any particular size or proportion of parts.

Adjacent the gear wheel 7, and preferably rotatably loose upon the shaft 6 is a ratchet wheel 9 attached to which, or formed integrally therewith, is a hollow drum 10 arranged longitudinally of said shaft with its axis and the axis of the shaft coinciding. It is to be noted that the ratchet wheel 9 is upon the opposite side of the gear wheel 7 from the adjacent side frame 5, and that the drum 10 extends from the ratchet wheel to the opposite side frame 5. At this opposite or free end, the drum is supported at its periphery in an annular guide 11 secured to the side frame 5 as by a rivet 12, and within the drum and surrounding the shaft 6 is a spring 13 one end of which, as 14, is secured to the side frame 5 at the open end of the drum, the opposite end 15 being made fast to the ratchet wheel 9. Obviously, as the drum is rotated by hand or otherwise, the spring 13 will be wound up and serve to rotate the drum in the opposite direction when released; and preferably 85 means are provided for connecting the drum, when so rotating in this opposite or working direction, under the action of the spring, to the gear wheel 7 and thus propelling the vehicle. To this end, a pawl 16 90 is pivoted upon the gear wheel 7 with its end pressed toward the teeth of the ratchet wheel 15 in any suitable manner, as by means of the leaf spring 17 shown in the drawings secured to the gear wheel 7. Ob- 95

viously other connecting or clutch means could be used, and furthermore it is within the scope of the invention to arrange the pawl and ratchet or other clutch means so as to actuate the gear wheel 7 as the spring 100 is wound up and allow the drum to rotate independent of the gear wheel as the spring unwinds, if so desired. It is preferable however to cause the unwinding of the spring to propel the vehicle, and allow the 105 vehicle to stand still as the spring is being wound up.

For winding the spring, I have shown a flexible member or cord 18 wound upon the drum 10 and extending at its free end from the rear of the vehicle. It will of course 110 be understood that the cord 18 is wound

upon the drum in the proper direction, so that drawing upon said cord to unwind it from the drum causes the spring to be wound up. Although I have shown the 5 cord entering from the rear of the vehicle, so as to trail behind the same and not become entangled as the vehicle travels along the floor, it will be understood that said cord may be introduced at any convenient part 10 of the vehicle. Preferably, a ratchet 36 is pivoted upon the side frame 5 engaging the gear wheel 7 to prevent it from turning backward and to enable a rearward pull upon the string to wind the spring 13 sufficiently 15 for operating purposes without dragging the toy backward. Then when the string is dropped or slackened, the toy runs forward and the string winds up again.

20 Mounted upon the vehicle for the amusement of a child and for attracting his attention is a movable member 19, here shown for illustrative purposes to be a donkey. This movable member or donkey 19 is shown 25 pivoted upon a post 20 which is secured to and projects upwardly from the top 21 of the frame of the vehicle. Stays 22, 22 extend from the donkey to the pivot, supporting said donkey thereon, and depending 30 from these stays fast with respect thereto is an arm 23 adapted to be swung back and forth to rock the donkey or movable member upon its pivot.

At a distance from the post 20 upon the 35 top of the frame of the vehicle is an upwardly extending bracket 24 in which is fulcrumed a rocking lever 25, said rocking lever extending laterally as at 26 and then upwardly as at 27 on one side of the fulcrum and extending downwardly as at 28 on the other side of the fulcrum. Preferably 40 said rocking lever is mounted so as to swing substantially in the plane in which the arm 23 swings, and is connected at its upper 45 end by means of a link 29 to the lower end of the arm 23. Obviously, therefore, as the rocking lever is oscillated upon its fulcrum the donkey will be correspondingly rocked. The depending portion 28 of the rocking 50 lever is proportioned and positioned so as to normally be adjacent at its lower free end to the periphery of the drum, preferably near one end thereof, and secured to the drum in any suitable manner, as by soldering, are cams 30 adapted to engage the said 55 depending portion 28 of the rocking lever, as the drum is rotated, and thereby swing the said rocking lever away from its normal position. Said cams are shown as pieces of 60 wire each providing an end portion 31 secured longitudinally of the drum upon the same, and an opposite end portion 32 parallel to said drum and offset therefrom by means of a connecting portion 33 disposed 65 radially with respect to the drum. Any

other similarly equivalent detail construction could be employed, however.

A suitable spring 34 is provided for maintaining the rocking lever in normal position, and said spring may be arranged in any 70 manner suitable to the purpose, it being here shown as secured to the top of the vehicle frame and extending upwardly therefrom and provided with a resilient loop 35 from which extends a lateral end slidably engaging the upper portion 27 of the rocking lever 25. As the drum is rotated, the cams 30 fast upon the drum swing the rocking lever, and as soon as disengaged, said rocking lever is swung back again by means of the spring 34. It will be obvious that the donkey will be rocked independent of the rotation of the wheels of the vehicle, in case of any breakage between the wheels and motor, since the actuation of the donkey is 80 made direct from the motor.

Obviously detail modifications may be made in manufacturing my improved toy without departing from the spirit and scope of the invention, and I do not wish to be understood as restricting myself, except as required by the following claims when construed in the light of the prior art.

Having thus described the invention, what I claim is:

1. In a toy, a vehicle having a driving wheel, a gear wheel for driving said driving wheel, a drum, means for rotating said drum in one direction, means for rotating said drum in the opposite direction, means for driving said gear wheel from the drum when said drum rotates in one direction, a movable member pivoted on said frame, an arm fast with respect to said member, a rocking lever pivoted to said frame and connected to said arm to swing the same, and an arm on said drum adapted to engage and swing said rocking lever as the drum rotates.

2. In a toy, a vehicle having a driving wheel, a gear wheel for driving said driving wheel, a drum, means for rotating said drum in one direction, means for rotating said drum in the opposite direction, means for driving said gear wheel from the drum when said drum rotates in one direction, a movable member pivoted on said frame, an arm fast with respect to said member, a rocking lever pivoted to said frame and connected to said arm to swing the same, an arm on said drum adapted to engage and swing said rocking lever from normal position to one side at each revolution of the drum, and a spring for returning said rocking lever to normal position.

3. In a toy, a body portion, a member pivoted on said body portion, an arm for swinging said member, a rocking lever mounted on the body portion, a link connecting said rocking lever to said arm, a

spring holding said rocking lever in normal position, a motor, and means on said motor for tripping said rocking lever.

4. In a toy, a body portion having wheels, 5 a shaft extending between the sides of said body portion, a drum loose on said shaft having a closed end providing a bearing therefor and its other end being open, an annular guide on the frame for said open 10 end, a helical spring on said shaft within

said drum having one end fast to the closed end of the drum and its other end fast to the body portion, a cord wound on said drum, and means for transmitting motion from said drum to the wheels of the body 15 portion.

STANISLAO CILETTI.
